UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed November 12, 1923. Serial No. 674,183.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to introducing and 10 controlling the work-sheets in a front-strike typewriter for use in keeping accounts and the like.

Usually a long sheet is retained in the typewriter to receive carbon-impressions of 15 the entries that are made on successive individual sheets. The record-sheet with its carbon remains in the machine while each individual sheet is released and withdrawn and replaced by a succeeding individual 20 sheet.

The individual sheets may be in the nature of cards or heavy paper, such as employed by banks for receiving entries from time to time for its various customers, each 25 customer's account having one sheet upon which entries are made from day to day. These individual sheets are thrust down at the front of the platen while the record-sheet and carbon remain in place around the 30 platen. One of the objects of the invention is to improve the means for retaining the record-sheet in the machine. The record-sheet which is wider than the individual sheet, is held by its side margins against the platen while the individual sheets are 35 removed, its holding means being usually applied to the record-sheet to press the same against the platen at points above the printing line. The individual sheets are apt to disarrange the record-sheet when the 40 latter has advanced so far that its bottom edge is only a short distance below the printing line.

To overcome this difficulty, the present 45 improvement provides spring-pressed fingers or devices to press the record-sheet against the platen below the printing line, and preferably just back of the front-feed-rolls, which run upon the under side of the platen. These detaining devices are connected 50 to the rock-shaft which releases the feed-rolls. This shaft extends along the under side of the platen. When the release is depressed, the rockshaft turns and permits the spring-pressed fingers or plungers 55

to pass up through holes in the paper-apron and press the record-sheet against the platen, thus detaining the same while the released individual work-sheets are pulled out and replaced by others. Owing to this provision, the record-sheet can remain in the machine for many more lines of record to be placed on the bottom portion thereof than has been practicable heretofore. These holding fingers can be connected to collars 60 which are secured by screws upon said releasing shaft, so that they may be adjusted along the shaft to any required points. The paper-apron can be perforated at the point required for the plunger to pass up therethrough against the paper. A clear path is presented over the apron for the leading edge of the front-introduced individual work-sheet.

Machines for this purpose generally have 75 platens and platen-carriages of great length, and much time is lost in reaching for and finding the release-key when it is desired to withdraw an individual sheet and insert another, said release-key being 80 at variable distances from the hand of the operator according to the position of the carriage, and often at a great distance from said hand.

A feature of the invention is the provision of means whereby, with either hand, and from any point along the platen, at the front of the latter, the operator may release the feed-rolls; thus obviating the necessity of movement of the operator's 85 hand to the end of the carriage, as heretofore.

A feature of the invention is a feed-roll-releasing bar extending lengthwise of the platen, the full length thereof, and 90 having means on each of the side pieces of the platen-carriage for supporting the same, in such manner that the bar may comprise part of a stiff bail movable as a unit, to have the same feed-roll releasing 95 action no matter what point thereof is struck by the operator.

Other features and advantages will hereinafter appear.

In the accompanying drawings, 105 Figure 1 is a view, in end elevation, partly cross-sectional, of the platen-carriage and associated parts of a typewriting machine embodying the present invention.

Figure 2 is a detail perspective view of 110

one of the record-sheet retaining clips and mounting thereof.

Figure 3 is a front view of the apparatus shown in Figure 1.

5 Figure 4 is a top plan view of the apparatus shown in Figures 1 and 3.

A platen 10, by means of an axle 11, is journaled in the side pieces 12 of the platen-frame. This frame is shiftable up and 10 down between case-positions by any suitable mechanism, not shown. For supporting the platen-frame and assisting in the case-shift of the latter, pins 13 on the side plates of the platen-frame are set upon arms 14 15 fast to a rock-shaft 15, upon which shaft is a spring, not shown, tending to lift the platen-frame. The case-shifting mechanism may be that shown in the standard Underwood typewriting machine.

20 The platen-frame is also provided with a paper-shelf 16, which forms an extension of the usual rear paper-table 17 and apron-extension 18, for guiding work-pieces down behind the platen and around under the 25 same to the printing line at the front thereof. The usual front feed-rollers 19 are also provided. The front rolls 19 are on a shaft 21, seated on the arms 22 of bell-crank levers pivotally mounted on a shaft 23, secured 30 to the end plates 12 of the platen-frame. The bell-crank levers which comprise the arms 22 have other arms 26 which depend to the rear of a shaft 27. Leaf-springs 29, bearing upon the arms 22, tend to rock the 35 arms upward to throw the feed-rolls against the platen, and therefore tend to press the arms 26 against the shaft 27. The shaft 27 has flats 30 cut therein where the arms 26 engage the same. When the feed-rolls are 40 in effective position, the arms 26 bear against the flats 30. When, however, the shaft 27 is rotated, the arms 26 are forced rearward to draw down the feed-rolls. The shaft 27 is journaled in the side plates 12 of the 45 platen-frame. The feed-roll mechanism, just described, is that found in the standard Underwood typewriting machine.

50 For throwing off the feed-rolls, the following device is employed. Fast to the shaft 27 is an arm 31, which is connected at one end to a link 32; the other end of the link 32 being connected to a bell-crank lever 33 on a stub-shaft 34, mounted in the right-hand side plate of the platen-frame. 55 One arm 35 of this bell-crank lever connects with a link 36, which extends forward and connects at 37 to one arm 38 of a bell-crank lever fixed to a rock-shaft 39. The rock-shaft 39, at its ends, has bearing in 60 brackets 40 secured to the side pieces 41 of the carriage. The bell-crank lever, of which the arm 38 forms a part, also has a forwardly-extending arm 44 which supports the right-hand end of a bar 45. The left- 65 hand end of this bar 45 is supported by an

arm 46, also made fast to the rock-shaft 39. Pressure on bar 45, as by the palm, at any point of the bar, results in movement of the bar from the dotted-line Figure 1 position to the full-line Figure 1 position, thereby 70 causing the link 36 to be drawn forward, bell-crank arm 35 to be rocked counterclockwise, and the link 32 to be drawn up to release the feed-rolls. Lips 47, offset from the lower edges of the bar-supporting 75 arms 44 and 46, by engagement with the carriage side pieces 41, determine the downward movement, and roll-releasing position, of the bar 45.

It will be noted that the link 36, which connects that part of the feed-roll-releasing mechanism which is on the shiftable platen-frame to that part of the feed-roll-releasing mechanism which is on the carriage, is 80 slightly inclined downward and rearward when the shift-frame is in lower-case position. When the shift-frame is in upper-case position, this link 36 is inclined slightly upward and rearward; the true medial position of the link 36 being a horizontal position halfway between its case-positions. By 85 this means, provision is made for the same roll-releasing action of the parts whatever the case-position of the shift-frame. It will be understood that the carriage has movement, in the usual manner, in letter-feed and return directions, on the main frame 90 95 100 105 110 115 120 125 130 48 of the machine. At its rear, the carriage rides upon a rail 49 on the main frame, and, at its front, the carriage is provided with a roll 50, which travels on a runway 51 on the main frame.

In the drawings, a record-sheet 52, faced by a carbon-sheet 53, is shown as having been fed down the table 16 and around the platen, and as having the typed portion thereof extending rearward over the top of the platen. The carbon-sheet is shown as having its leading end turned, at 54, over the leading end of the record-sheet, so that the two sheets may be fed into the machine and around the platen as a unit, without slipping of one on the other. The record-sheet, as hereinafter explained, is to receive the entries made successively upon a series of individual statements; and, in order that the record-sheet may be held in place upon the platen while the feed-rolls are released for the insertion and removal of the individual statements, a pair of clips are provided. These clips are shown as consisting of spring-fingers 55, carrying rollers 56, which are adapted to bear upon the record-sheet on the platen beyond the side margins of the individual statement-sheets.

The spring-fingers 55 are secured to a shaft 58. The shaft 58, in turn, is supported by U-shaped pieces 59, secured to blocks 60 on the side plates 61 of a frame which is set upon and detachably secured to the

flanges 62 on the side pieces 12 of the platen-frame. The shaft 58 is revoluble in the brackets 59, but is held against accidental rotation by means of rollers 63 on the brackets 59, which set into a slot 64 extending longitudinally the full length of the shaft 58. Leaf-springs 65 on the brackets 59 hold the rolls 63 in the slot 64, but yield to permit the rolls 63 to cam themselves out of the slot 64, for rotation of the shaft 58 when desired. When pressure is applied to the clips 55 to throw the same up to release the record-sheet, the springs 65 yield to permit the shaft 58 to turn.

15 The shaft 58 also serves as a support for a table or container 70 for the blank statement-sheets or bill-heads 71. For supporting the table 70 on the shaft 58, there is riveted to the rear wall of the table a bar 20 75. This bar, beyond the sides of the table 70, has its ends offset downward at 76, and rearward at 77, for attachment to U-shaped brackets 78, similar to the brackets 59. These brackets 78 are connected to the shaft 25 58 by rollers 79, set in the slot 64 in the shaft, and held therein by springs 80, in the same manner as the rollers 63. Although this form of attachment of the table 70 to the shaft 58 permits angular movement of 30 35 the table, if desired, the prime purpose of such attachment is to permit the table to be slid rightward or leftward along the shaft to any desired position on the carriage. The rollers 79 and slot 64 obviously make a spline connection of the table to the shaft 58; and the pressure of the springs 80 is sufficient to hold the table against accidental rightward or leftward displacement. It follows, therefore, that the table 40 45 is placeable and detachable as a unit with the frame which carries the shaft 58 and paper-clips 55; so that, when this detachable frame is not present on the machine, the machine may be used in the ordinary way without unnecessary incumbrances.

In operation, the record-sheet 52 and carbon 53 are fed around the platen to typing position, when the feed-rolls 19 are in effective position, by means of the usual hand-wheels 81 on the platen-axle 11, or by means of the usual line-space mechanism, of which only a ratchet-wheel 82 on the platen-axle is shown. The paper-finger rollers 56, if not previously applied, are then applied to 55 60 65 the record-sheet. The operator then passes a statement-sheet or card down in front of the platen, in front of the carbon-sheet. As the operator's hand moves downward, the operator's palm strikes the bar 45 at some point thereof, and throws off the feed-rolls, permitting the lower edge of the statement-sheet to be passed around the platen between the latter and the apron 18. When the statement-sheet or card is in printing 65 position on the platen, the operator's hand

is lifted to release the bar 45 and to permit the springs 29 to throw the pressure-rolls to position for holding the statement-sheet.

After typing on a statement-sheet is completed, the carriage is thrown rightward for commencement of writing on another statement-sheet. The lever by which the carriage is thus returned, ordinarily effects a single line-space movement of the platen by mechanism not here shown. This results in a line-space movement of the record-sheet 70 75 80 85 90 95 100 105 110 115 120 125 130 52 and carbon 53 so as to prepare the same for receiving the entries to be made upon the next succeeding statement-sheet.

It has hereinbefore been stated that one of the objects of the invention is to provide means for retaining the record-sheet to prevent disarrangement of the record-sheet when the latter has advanced so far that its bottom edge is only a short distance 85 below the printing line. The means for this purpose shown in the drawings comprises a pair of clips 83 of spring metal (see Figure 2), secured to collars 84 held to the feed-roll release-shaft 27 by set screws 85. When the set screws 85 are loosened, the collars 84 with the clips 83 are adjustable lengthwise of the platen, along the shaft 27, according to the width of the record-sheet, or position of the same on the 95 platen. In order that the collars 84 may be located on the shaft 27, clear of the roll-supporting arms 22 and other parts, the clips 83 are shown as comprising portions or arms 86 extending lengthwise of the platen, laterally outward from spring U-shaped portions 87 of the clips at the collars. At the distal ends of the clip arms 86, fingers 88 are upturned therefrom. The fingers, which are the parts of the clips which press upon the record-sheet, have their ends rolled over at 89 to prevent fouling of the paper thereon.

As shown in Figure 1, the clips 83 are secured to the top of the shaft 27, and have 110 the U-shaped portions 87 thereof turned rearward, upward, and forward, over the shaft 23, to clear the latter, and to position the fingers 88 just behind the feed-rolls 19. The fingers pass upward to the platen through openings 90 in the forward portion 115 of the apron 18; and thus bear upon the record-sheet 52 and on the carbon-sheet 53 at the front portion of the platen, below and near the printing line; and beyond the 120 side margins of the individual statement-sheets or cards (see Figure 3).

Normally, or in the typing position of the parts, the fingers 88 do not bear upon the record-sheet, and therefore do not interfere 125 with line-space feed thereof. When, however, the shaft 27 is rocked clockwise (Figure 1) to release the feed-rolls 19, the clips 83 are moved against the platen to hold the record-sheet and carbon (as shown in Fig-

ure 1) while the rolls are in released position. The proximity of the fingers 88 to the printing line permits of effective holding of the record-sheet, against displacement during the removal and insertion of work-pieces, even though the record-sheet has been advanced until its bottom edge is almost at the printing line. The movement of the shaft 27, in the re-application of the 10 feed-rolls, causes the holding fingers 88 again to be withdrawn from the record-sheet.

As in patent to Jesse A. B. Smith, No. 1,402,804, dated January 10, 1922, here also 15 the usual rear feed-rolls are omitted. The omission of rear feed-rolls permits elimination of holes therefor through the apron 18; and the apron, rearward of the front feed-rolls, may therefore be smooth and continuous, with nothing for work-pieces to catch onto or foul when such work-pieces are inserted from the front of the platen, rearward over the apron. The holes 90 for the 20 clip fingers 88 may be cut in the apron 18 at any desirable or suitable points thereof.

Variations may be resorted to within the scope of the invention, and portions of the improvements may be used without others.

Having thus described my invention, I 30 claim:

1. In a front-strike typewriting machine, a platen, spring-clips, below the printing line, effective upon a record-sheet on the platen, but ineffective upon an overlying statement-sheet, for retaining the record-sheet against disarrangement on the platen, and a rock-shaft on which the spring-clips are mounted for movement between effective and ineffective positions. 35
40 2. In a front-strike typewriting machine, a platen, spring-clips, below the printing line, effective upon a record-sheet on the platen, but ineffective upon an overlying statement-sheet, for retaining the record-sheet against disarrangement on the platen, a rock-shaft on which the spring-clips are mounted for movement between effective and ineffective positions, feed-rolls, and means whereby the rock-shaft may release 45 the feed-rolls in the movement thereof which renders the clips effective. 50

3. In a front-strike typewriting machine, a platen, means, below the printing line, effective upon a record-sheet, but ineffective 55 upon an overlying statement-sheet, for retaining the record-sheet against disarrangement on the platen, a rock-shaft on which the retaining means are mounted for movement between effective and ineffective positions, and means for adjusting the position 60 of the retaining means on the rock-shafts, lengthwise of the platen.

4. In a front-strike typewriting machine, a platen, an apron for guiding a record-sheet down around under the platen, to the

front from the rear thereof, means, below the printing line, effective upon a record-sheet, but ineffective upon an overlying statement-sheet, for retaining the record-sheet against disarrangement on the platen, 70 and means for throwing the retaining means to effective position against the platen; the apron having holes through which the retaining means may strike to the platen.

5. In a typewriting machine, a platen, an 75 apron for guiding a record-sheet down around under the platen, to the front from the rear thereof, feed-rolls at the front of the apron co-operating with the platen, means adjacent the feed-rolls for retaining 80 the record-sheet against disarrangement on the platen, and means for moving the retaining means between effective and ineffective positions; the apron having holes through 85 which the retaining means may strike to the platen.

6. In a typewriting machine including a platen and typing instrumentalities, means for introducing an outer individual work-sheet around the platen from the front of the machine to receive typing thereon and removing said individual sheet while an inner record-sheet of greater width than said individual sheet is held to the platen, said means comprising a paper-apron beneath 90 said platen, feed-rolls at the front of the paper-apron for feeding both said individual work-sheet and said record-sheet, retaining means to hold said record-sheet to the platen at points beyond the side edges 95 of said individual work-sheet, close to and below the typing line, means to hold said record-sheet to the platen beyond the typing line, and castoff means to conjointly operate 100 said feed-rolls and said retaining means, said cast-off means in one position applying 105 said retaining means and casting off said feed-rolls, said paper-apron presenting an unobstructed path for the leading edge of said front-introduced individual work-sheet, 110 and in another position casting off said retaining means and applying said feed-rolls. 115

7. In a typewriting machine including a platen and typing instrumentalities, means for introducing an individual work-sheet 120 around the platen from the front of the machine to receive typing thereon and removing said individual sheet while a condensed record-sheet is held to the platen, said means comprising a paper-apron beneath 125 said platen, feed-rolls mounted adjacent the front of said apron for feeding both said individual work-sheet and said condensed record-sheet, clips co-operative with the platen to hold said record-sheet to the platen close to and below the typing line, means to hold said record-sheet to the platen above the typing line, and cast-off means to 130 conjointly operate said feed-rolls and said clips, said cast-off means in one position

rendering said clips effective and said feed-rolls ineffective, said paper-apron presenting a clear path for the leading edge of said front-introduced individual work-sheet, and in another position rendering said clips ineffective and said feed-rolls effective.

8. In a typewriting machine including a platen and typing instrumentalities, means for introducing an outer individual work-sheet around the platen from the front of the machine to receive typing thereon and removing said individual sheet while an inner record-sheet of greater width than said individual sheet is held to the platen, said means comprising a paper-apron beneath said platen, feed-rolls mounted at the front of said apron to engage the platen for feeding both said individual work-sheet and said record-sheet, clips cooperative with the platen to hold said record-sheet to the platen, said clips mounted to project through said apron at points beyond the side edges of said individual work-sheet, close to and below the typing line, paper-fingers mounted above the platen to hold said record-sheet to the platen beyond the typing line, and cast-off means to conjointly operate said feed-rolls and said clips, said cast-off means in one position applying said clips and casting off said feed-rolls, said paper-apron presenting an unobstructed path for passage of said individual work-sheet, and in another position casting off said clips and applying said feed-rolls.

9. In a typewriting machine, a carriage, a platen, a platen-frame on said carriage shiftable to an upper-case position and having side pieces, feed-rolls to co-operate with the platen, a rock-shaft having bearings at both side pieces of the platen-frame, and a feed-roll-releasing bar operatively connected to the rock-shaft and extending lengthwise of the platen, said feed-roll-releasing bar mounted on the carriage.

10. In a typewriting machine, a carriage, a platen, a platen-frame shiftable to an upper-case position and having side pieces, feed-rolls to cooperate with the platen, a rock-shaft having bearings at both side

pieces of the platen-frame, and a feed-roll-releasing bar mounted on the carriage and extending the full length of the platen, said rock-shaft operatively connected to said feed-rolls and to said releasing bar and operable in either case-position of said platen-frame.

11. In a typewriting machine including a platen and typing instrumentalities, means for introducing an individual work-sheet around the platen from the front of the machine to receive typing thereon and removing said individual sheet while a condensed record-sheet is held to the platen, said means comprising a paper-apron beneath said platen, feed-rolls mounted adjacent the front of said apron for feeding both said individual work-sheet and said condensed record-sheet, clips cooperative with the platen to hold said record sheet to the platen close to and below the typing line, means to hold said record-sheet to the platen above the typing line, and cast-off means to conjointly operate said feed-rolls and said clips, said cast-off means in one position rendering said clips effective and said feed-rolls ineffective, said paper-apron presenting a clear path for the leading edge of said front-introduced individual work-sheet, and in another position rendering said clips ineffective and said feed-rolls effective, said cast-off means including a rock-shaft for oppositely actuating said feed-rolls and clips, and a releasing bar operatively connected to said rock-shaft and mounted to extend the full length of the platen at the front of the machine.

12. In a typewriting machine, a platen, feed-rolls to co-operate with the platen, a bar extending lengthwise of the platen, at the front thereof, for releasing feed-rolls, means for retaining a work-piece against disarrangement on the platen when the bar is actuated to release the rolls, and means for automatically throwing the retaining means to ineffective position when the bar is released.

JESSE A. B. SMITH.
